CLAIM

We claim the ornamental design for a remote control flying vehicle, as shown and described.

DESCRIPTION

FIG. 1 is a top front perspective view of the remote control flying vehicle of the present invention.

FIG. 2 is a bottom rear perspective view of the remote control flying vehicle of FIG. 1.

FIG. 3 is a front elevation view of the remote control flying vehicle of FIG. 1.

FIG. 4 is a rear elevation view of the remote control flying vehicle of FIG. 1.

FIG. 5 is a side elevation view of the right side of the remote control flying vehicle of FIG. 1.

FIG. 6 is a side elevation view of the left side of the remote control flying vehicle of FIG. 1.

FIG. 7 is a top plan view of the remote control flying vehicle of FIG. 1; and,

FIG. 8 is a bottom plan view of the remote control flying vehicle of FIG. 1.

In the drawings, the broken lines depict portions of the remote control flying vehicle that form no part of the claimed design.

1 Claim, 8 Drawing Sheets
